UNITED STATES PATENT OFFICE.

EDGAR B. SYMONS, OF HOLLYWOOD, CALIFORNIA, ASSIGNOR TO SYMONS BROTHERS COMPANY, OF MILWAUKEE, WISCONSIN, A CORPORATION OF SOUTH DAKOTA.

FEED SPOUT FOR DISK CRUSHERS.

Application filed November 13, 1925. Serial No. 68,746.

My invention relates to feeding means for disk crushers and particularly to a feeding spout adapted to feed the material to be crushed to the crushing space defined by a

5 pair of opposed crushing disks. It has for one purpose to provide a spout of the type shown adapted to feed material to the space between a pair of opposed concave disks, the spout penetrating one of said disks. 10 Another object is the provision of a removable and reversible lining for such a spout. Another object is the provision of a removable discharge lip for such a spout. Other objects will appear from time to time in the 15 course of the specification and claims. I illustrate my invention more or less diagrammatically in the accompanying drawings wherein—

Figure 1 is a vertical longitudinal section 20 along the axis of rotation of the disks;

Figure 2 is a section on the line 2—2 of Figure 1; and

Figure 3 is a section on the line 3—3 of Figure 1.

25 Like parts are indicated by like symbols throughout the specification and drawings.

A is any suitable crusher supporting member positioned on a base A¹ and adapted to support a bearing fragmentarily shown as A² in Figure 1. Rotating in such 30 bearing is the hollow shaft B terminating in an outwardly flared cup portion B¹ with an interior spherical surface B², terminating in an outwardly projecting circumferential flange B³.

C is a solid shaft adapted to rotate within the hollow of the shaft B, the axes of the two shafts being slightly inclined to each other. C¹ is a spherical surfaced head at 40 the end thereof adapted to conform to the opposed spherical surface B² which it engaged by means of a babbitt bearing member C².

D is a centrally apertured carrying plate 45 having a circumferential rearwardly positioned flange D¹ adapted to be secured to the circumferential flange B³ of the hollow shaft B, for example by means of the bolts D², nuts D³, and spacers D⁴.

50 E and E¹ are opposed concave disks mounted one on the member C¹ and the other on the member D, and adapted to define a lenticular crushing space. The means

of attaching these disks forms no part of the present invention and are not described 55 in detail. The disk E¹ is centrally apertured as at E².

G is a feed spout supported on any suitable frame work, for example by the supports G¹. It terminates just short of the 60 disk E¹ and is provided with a removable lip G², of any suitable refractory material, for example manganese steel. The lip is provided with the rearwardly projecting arms G³ adapted to seat in the depression G⁴ in the sides of the chute G. The arms terminate in outwardly flanged lips G⁵ perforated at G⁶ to admit the passage of a securing bolt G⁷ the opposite end of which passes through the outwardly projecting 70 ears G⁸.

H is a removable liner for the chute, preferably constructed of manganese steel or some other suitable refractory material. It includes a thicker central portion H¹ with 75 the thinner side portions H² projecting upwardly from it and conforming to the interior of the chute. H³ is a lug positioned intermediate the ends of the member H and apertured as at H⁴ to receive a securing pin 80 H⁵. It will be understood that the lug passes through an aperture H⁶ in the bottom of the chute. The size of the liner, the position of the lug and the location of the aperture are such that the liner may be reversed to position its upper end, when worn, at the bottom of the chute.

The use and operation of my invention are as follows:

My spout is adapted for employment with 90 a crusher in which a pair of opposed disks are rotated in unison about a generally horizontal axis, the axes of the two disks being slightly inclined in such fashion as to vary the clearance or the distance separating corresponding points upon the two disks as the disks rotate. One of the disks is mounted on a centrally apertured holder and is itself centrally apertured to permit the penetration of the discharge end or lip of the 95 spout. The material to be crushed is discharged into the upper end of the spout, passes downwardly by gravity through the spout, passes over the lip and into the lenticular space defined by the opposed concave 100 disks. The two major points of wear on 105

the spout are the lip and the bottom of the upper end of the spout. When the crusher is operated under forced feed and the spout is filled with material and material is heaped 5 up above the top of the spout the bottom of the spout is protected from the shock or abrasion of fragments dropped from above by the fragments already resting upon the spout bottom and moving downwardly 10 therealong as the material undergoing crushing is discharged from the crushing zone. At such time, however, the crushing zone being substantially filled with fragments undergoing reduction, there is a very 15 heavy wear about the edge or lip of the discharge end of the chute. When the crusher is operating under light feed, on the contrary, the crushing zone is relatively sparsely occupied with material undergoing 20 crushing and the wear against the edge or lip of the inner edge of the spout is much lighter. However the fragments of material falling from above upon the bottom of the upper or outer end of the spout tends 25 to abrade or wear away the bottom of the spout.

I provide a spout in which these heavy wear taking areas are protected by removable members which may be replaced when 30 worn, without necessitating replacement of the entire casting. In order to protect the discharge edge or lip of the spout I provide a removable rim or ring, preferably of manganese steel or some other refractory 35 or wear resisting material. This ring is provided with two arms which seat in slots or notches in the sides of the discharge spout and terminate in outwardly turned flanges apertured in line with flanges or ears on the 40 supporting frame work or base of the crusher. Securing bolts pass through the apertures and are tightened down with nuts to draw the rim or ring firmly against the end of the spout. Preferably the interior 45 of the spout increases in diameter toward the crushing zone, the edge furthest from the crushing zone being of somewhat greater thickness than the spout wall.

In order to protect the bottom of the 50 spout I provide a removable and reversible liner which increases in thickness from the edges toward the middle. The center of the bottom of the liner is provided with an apertured lug adapted to pass through a 55 slot in the bottom of the spout. When so positioned a bolt or other fastening means may be passed through it, holding it firmly in place. The thickness of the liner is preferably such as to raise its bottom somewhat 60 above the inner edge of the ring or lip, as shown in Figure 1. Thus the liner cannot be so far worn down as to be below the inner edge of the ring. The liner being identical at each end and its lug being equi- 65 distant from the ends, it may be reversed.

This is particularly important since the wear upon the liner is normally far more rapid at the upper than at the lower end.

It will be realized that whereas I have illustrated an apparatus particularly adapted 70 for my purpose that nevertheless I do not wish to be limited to the specific description and showing herein. Many changes might be made in size, shape, number and disposition of parts without departing from 75 the spirit of my invention and I therefore wish my disclosure to be taken as in a broad sense illustrative or diagrammatic.

I claim:

1. In a delivery spout liner for horizontal disk crushers having a spout member the lower end of which is aligned with a central aperture in one of said disks, a removable liner body for the bottom of said spout, and a lug downwardly depending from the bottom of said liner and adapted to penetrate the spout bottom. 80

2. In a delivery spout liner for horizontal disk crushers having a spout member the lower end of which is aligned with a central 85 aperture in one of said disks, a removable reversible liner body for the bottom of said spout, and a lug downwardly depending from the bottom of said liner at a point substantially equi-distant from its ends, said 90 lug being adapted to penetrate the spout bottom.

3. In a delivery spout liner for horizontal disk crushers having a spout member the lower end of which is aligned with a central aperture in one of said disks, a removable liner body for the bottom of said spout, and a lug downwardly depending from the bottom of said liner and adapted to penetrate the spout bottom, said lug being aper- 100 tured to receive a securing member. 105

4. In a delivery spout liner for horizontal disk crushers having a spout member the lower end of which is aligned with a central aperture in one of said disks, a removable, reversible liner body for the bottom of said spout, comprising a member the lower face of which is adapted to conform in shape to the spout bottom, such member being transversely of unequal thickness, the 110 edges being thinner than the central portion, and being upwardly and inwardly inclined at its ends. 115

5. In a delivery spout liner for horizontal disk crushers having a spout member the lower end of which is aligned with a central aperture in one of said disks, a removable, reversible liner body for the bottom of said spout, such liner body being equal in length to the length of the spout 120 with which it is used, and reversible securing means associated with said liner. 125

6. For use with a horizontal disk crusher having a spout member the lower end of which is aligned with and closely ap- 130

proached to the central aperture of one of the disks, a removable lip associated with the inner end of such spout and adapted to penetrate and be positioned in the central aperture of such disk.

7. For use with a horizontal disk crusher having a spout member the lower end of which is aligned with and closely approached to the central aperture of one of the disks, a removable lip associated with the

inner end of such spout and adapted to penetrate and be positioned in the central aperture of such disk, said lip having a pair of rearwardly projecting arms adapted to penetrate channels in such spout.

15

Signed at Hollywood county of Los Angeles and State of California, this 7th day of November, 1925.

EDGAR B. SYMONS.
